UNITED STATES PATENT OFFICE.

SOLOMON DAVIS, OF NEW YORK, N. Y.

SEWING-MACHINE ATTACHMENT.

996,467.

Specification of Letters Patent. Patented June 27, 1911.

Application filed June 2, 1910. Serial No. 564,620.

To all whom it may concern:

Be it known that I, SOLOMON DAVIS, citizen of the United States, residing at New York, in the county of New York and State 5 of New York, have invented new and useful Improvements in Sewing-Machine Attachments, of which the following is a specification.

This invention relates to improvements in 10 sewing machine attachments in which rotary motion of a driven shaft is converted by means of suitable mechanism into slow rectilinear motion, the object being to slowly guide and feed the material toward the 15 needle of the machine.

The attachment is especially adapted for 20 sewing soft hat brims, but can be used for other purposes such as cloth buffing wheel disks, doilies, quilts, and similar useful and ornamental articles. By reason of the slow 25 feeding movement of the material toward the needle it is possible to sew a continuous spiral in the fabric. The width of the convolutions of the spiral may be varied by means of a device forming part of the attachment. The attachment can be fitted to 30 and arranged on any ordinary sewing machine. The attachment feeds the fabric toward the side of the needle, or parallel to the driving shaft of the machine to gage the 35 width of the convolutions of the spiral, while the ordinary feed of the machine feeds the fabric toward the front of the needle or at right angles to the driving shaft. Heretofore 40 in sewing a spiral in a hat brim, it has been necessary to feed the brim toward the side of the needle by hand.

In the accompanying drawings Figure 1 is 45 a side elevation of a sewing machine embodying this invention. Fig. 2 is a horizontal longitudinal section along the line $x-x$ of Fig. 1. Fig. 3 is a vertical section along the line $y-y$ of Fig. 1. Fig. 4 is a plan view of a hat brim, showing the convolutions partly sewed.

In this drawing the letter a designates a worm which is fastened to the driving shaft of an ordinary sewing machine. This worm engages a worm wheel b secured to a driven 50 shaft c which is journaled in supports fastened to the head and base plate of the machine. The said driven shaft is provided at its lower end with a worm e adapted to engage a worm wheel f fastened to a transmission 55 shaft g on which is slidably fastened a wheel h . The wheel h is normally in frictional

contact with a cone pulley i fastened to a counter shaft j . This counter shaft is also provided at one end with a gear k which engages a gear m fixed to a screw n . A nut p 60 is mounted on and engages the screw n and said nut has fastened to its lower end an arm carrying a guide plate q . This guide plate q has rollers r pivoted to its rear end located under the plate. The plate q has 65 slots v which serve as guides for the front rollers r' and these rollers are pivoted to a bar w . A spring 5 mounted on a stem 6 is in contact with the bar and tends to push the bar with the rollers r' toward the fabric. 70 A nut 7 is threaded on the stem 6 to adjust the compression of the spring.

The fabric is placed under the guide plate q and between the rollers r and r' . The rollers r' being slidably mounted will 75 take any irregular surface at the edge of the fabric, and by means of the spring 5 these rollers r' will equally or evenly guide the fabric.

The needle is indicated at t in Figs. 1 80 and 2.

The nut p is slotted at the top or U shaped, as shown in Fig. 3, so that it can be pushed downward to disengage it from the screw, and thus set to its initial position without reversing the machine. A series of springs s tend to press the nut into 85 frictional contact with the threads of the screw.

The screw n is journaled in a frame o 90 fixed to the bed-plate of the machine.

It will be seen that the wheel h on the transmission shaft can be set along said shaft to different positions on the face of the cone pulley, thereby producing changes 95 of speed in the counter shaft and the screw will revolve faster or slower, thus moving the nut with its guide plate and the material toward the needle at more or less speed and varying the spaces between the convolutions of stitches at will. 100

The transmission shaft is journaled in standards fastened to the bed-plate and is provided with a spring u whereby it is moved toward the counter shaft to hold the wheel h in frictional contact with the cone pulley. 105

It will be noticed that the respective rollers r and r' revolve when the material is fed toward the front of the needle. 110

Plates 8 are fastened to the head of the machine and extend downwardly to contact

or engage the guide-plate *q*. These plates serve to prevent lateral displacement of the said guide plate and steady the guide plate when it is moving forward.

5 I claim—

1. In a sewing machine attachment, the combination with a screw of a guide plate operated thereby, driving mechanism including a driven shaft, a transmission shaft 10 and a counter shaft for revolving the screw to impart rectilinear motion to the guide plate, a device carried by the transmission shaft the speed of which is substantially constant and operatively connected to the 15 counter shaft for changing the velocity of the screw.

2. In a sewing machine attachment, the combination with a screw of a guide plate adapted to engage the screw, mechanism 20 for revolving the screw to impart recti-

linear movement to the guide plate, and rollers located below and yieldingly connected to the guide plate to yieldingly engage a fabric.

3. A sewing machine attachment comprising a screw, a guide plate adapted to engage the screw, a counter shaft coupled to the screw and provided with a cone pulley, a transmission shaft having an adjustable wheel to operatively engage the cone pulley, and suitable mechanism for coupling the transmission shaft, to a moving part of a sewing machine.

In testimony whereof I have hereunto set my hand in the presence of two subscribing witnesses.

SOLOMON DAVIS.
